Inventor
William Bourne

UNITED STATES PATENT OFFICE.

WILLIAM BOURNE, OF BOSTON, MASSACHUSETTS, ASSIGNOR TO NATHANIEL CUMMINGS, OF SAME PLACE.

IMPROVEMENT IN PIANO-FORTES.

Specification forming part of Letters Patent No. 37,717, dated February 17, 1863.

To all whom it may concern:

Be it known that I, WILLIAM BOURNE, a citizen of the United States of America, and a resident of Boston, in the county of Suffolk and State of Massachusetts, have invented a new and useful Improvement in Piano-Fortes; and do hereby declare the same to be fully described in the following specification, and represented in the accompanying drawings, of which—

Figure 1 is a top view of the iron frame, the sounding-board, and the case of the instrument in their relative positions. Fig. 2 is a top view of the case and the sounding-board as they appear without the iron frame. Fig. 3 is a longitudinal section, and Fig. 4 a transverse section, of the case, the sounding-board, and the iron frame.

The principle or nature of my invention is found in an improved arrangement, which consists in extending the sounding-board in rear of the hammer-passage thereof and underneath the straining-pin bar of the iron frame, and from side to side and end to end of the case, and so suspending the said bar over the part of such board which is in rear of the hammer-passage that there may be a free and uninterrupted vibration-space between the two, substantially as hereinafter described.

In the construction of ordinary piano fortés it has been customary to extend along underneath and close against the straining-pin bar or plate of the iron frame a strong wooden backing or blocking, such filling a considerable portion of the case, and serving not only to strengthen it, but give support to the iron frame. This backing or blocking has been considered necessary to the construction of the instrument, the sounding-board being arranged in front of it, or between it and the front board of the case.

In carrying out my invention I entirely dispense with the said blocking, and within the space usually occupied thereby and in rear of the hammer-passage I arrange an extension of the sounding-board, or what perhaps may be more properly termed an "auxiliary sounding-

board," and between the upper surface of the said extension or auxiliary sounding-board and the lower surface of the straining-pin bar or plate I leave a space sufficient to admit of the free, uninterrupted vibration of the said auxiliary sounding-board or extension.

In the drawings, A is the case of the instrument; B, the metallic or iron string-frame; C, the sounding-board; a, the hammer-passage, which in this case consists of a slot made through the sounding-board. It is through this passage that the hammers ascend or pass in order to strike the strings. The sounding-board, near its edges, rests on a shelf or ledge, b. This shelf or ledge is arranged so as to project from the inner surfaces of the rear side and the two ends of the case. Furthermore, there is upon the upper surface of the sounding-board, and close to its edge or edges, an abutment, ledge, or projection, c, the same being formed and arranged as shown in Figs. 2, 3, and 4. It is on the upper surface of this abutment or ledge c that the iron frame B rests or is supported. In consequence of this ledge c there will be formed between the straining-pin bar b' (of the iron frame) and the part e (or the auxiliary sounding-board extended in rear of the hammer-passage a) a vibration-space, f, which may have a depth of about one-half an inch. By means of the ledge c the straining-pin bar b' becomes suspended or bridged over the extended part e or auxiliary sounding-board.

From the above it will be seen that by my improvement there is a material gain in the amount of sounding-board; also, that the usual heavy blocking used in rear of the sounding-board is dispensed with. In consequence of this latter, the whole case of the instrument is enabled to co-operate to better advantage with the sounding-board, or enables the latter to operate with a better musical effect than when the said backing or blocking is used.

It is found that my improvement is productive not only of a greater extent of vibration of the sounding-board and case, but a consequent increase in the volume of tone. The

instrument is rendered not only much more powerful, but less liable to get out of order or tune.

I claim—

My improved arrangement, the same consisting in extending the sounding-board in rear of the hammer-passage thereof and underneath the straining-pin bar of the iron frame, and from side to side and end to end of the case,

and so suspending the said bar over the part of such board which is in rear of the hammer-passage that there may be a free or uninterrupted vibration-space, *f*, between the two, substantially as hereinbefore described.

WILLIAM BOURNE.
